UNITED STATES PATENT OFFICE

ELVIN S. GOODSPEED, OF DETROIT, MICHIGAN, ASSIGNOR TO GENERAL MOTORS CORPORATION, OF DETROIT, MICHIGAN, A CORPORATION OF DELAWARE

HOIST

Application filed August 17, 1929. Serial No. 386,533.

This invention relates to hoists and has particular reference to a hoist of the overhead type adapted for lifting relatively light loads or loads which are slightly heavier than those which can be conveniently lifted by hand.

The hoist of the invention is intended for use in and about factories and is designed to be suspended over head, preferably by means of a cable or chain so that it is readily swingable to any convenient angle.

The hoist of the invention comprises a main housing on which an electric motor is mounted. The motor drives a shaft to which a worm is secured, the worm in turn driving a worm wheel keyed to a hollow shaft, the end of which projects beyond the housing and has one half of a clutch secured thereto. Concentric with the hollow shaft is a second hollow shaft which projects beyond both ends of the housing and has secured to one end the second half of the clutch. A gear secured to the other end of the inner shaft operates on a lift rack or bar which is adapted to lift the load. The rack has reciprocably mounted thereon a control rack or bar which is adapted to operate a gear loosely mounted on the inner shaft adjacent the rack operating gear. The freely mounted gear is internally threaded and is adapted to mesh with a threaded head mounted in a slot in and projecting beyond both sides of the shaft. The head has a rod secured thereto extending through the hollow shaft and is adapted to operate the clutch at its other end. By reciprocating the control rack, the freely mounted gear is rotatable which shifts the threaded head back and forth to connect or disconnect the clutch. The control rack is operated by means of a spring pressed handle mounted on the lifting rack.

The lifting rack is provided with a pair of projecting fingers positioned in parallel vertical planes which are adapted to make and break the electric circuit of the motor as the rack reaches one extremity of its movement.

On the drawings:

Figure 1 shows a plan view of the hoist.

Figure 2 is a section on the line 2—2 of Figure 1.

Figure 3 is a section on the line 3—3 of Figure 1.

Figures 4 and 5 are detailed sectional views of the clutch operating mechanism, the sectional views being taken at right angles to each other.

Referring to the drawings, the numeral 2 indicates the hoist as a whole. The hoist includes the main housing portion 4 having the eye 6 rigidly secured thereto at its uppermost portion. The purpose of the eye 6 is to allow the attachment of a cable or chain to suspend the hoist overhead. The hoist may also be rigidly mounted, if desired, but the swingable mounting is preferred.

A bracket 8 is rigidly mounted at one side of the housing 4 by means of the machine bolts 10 and on the bracket 8 the electric motor 11 is rigidly secured by means of the bolts and nuts 12. The electric wires or connections for the motor are not shown as their application is apparent to those skilled in the art. The motor drives the shaft 14 connected by means of a clutch 16 to a worm shaft 18 on which the worm 20 is rigidly mounted. The shaft 18 is mounted in suitable bearings 22 in the sides of the housing 4. A plate 24 surrounds the shaft 18 and is secured to the housing 4 by means of the bolts 26 which also pass through an annular flange on left hand cup-shaped bearing portion 25. The purpose of the plate 24 is to position the bearing 22 and to exclude dust from the interior of the housing and the bearing.

The worm 20 meshes with a worm wheel 28 secured by means of a key 30 to a short hollow shaft 32. The shaft 32 extends through a bearing portion 34 in a cover plate 36 secured to the housing by means of the machine bolts 38. At its outer end the shaft 32 has secured thereto by means of the keys 40, a dome 42 which houses and has secured thereto one half 44 of a clutch indicated as a whole at 46. The clutch is conventional and per se forms no part of the invention and any suitable type of clutch may be used.

A second or longer hollow shaft 48 is rotatably received within the hollow shaft 32 and projects into the dome 42 and beyond both sides of the housing 4. At the clutch

- or dome end of the shaft 48 the second half 50 of the clutch 46 is rigidly mounted by means of the keys 52. A disk or spider 54 is freely mounted on the shaft 48 inside the dome 42 5 and is secured to the shaft 48 by means of the slideable T-shaped key 56 received in a slot 58 in the shaft. The key 56 as well as the disk or spider 54 are slideably but not turnably mounted relative to the shaft 48.
- 10 The opposite end of the shaft 48 is mounted in a bearing stud portion 59 in the housing 4 and extends through a bearing portion 60 rigidly secured to the housing 4 by means of the machine bolts 62. The bearing portion 60 is hollow as indicated at 64 and in the hollow portion, there are received the gears 66 and 68. The gear 66 is rigidly mounted on the shaft 48 by means of the key 70 while the gear 68 is internally threaded 15 as indicated at 72 and is freely or loosely mounted on the shaft 48. The shaft 48 has a slot 74 beneath the gear 68 and in the slot there is received the head 76 having the threads 78 which engage with the internal threads 72 on the gear 68. A rod 80 is rigidly secured at one end to the head 76 in any suitable way such as by means of a non-circular fit or the riveted over-reduced portion 82, and at its opposite end in a similar 20 manner to the key 56. The rotation of the gear 68 (which is itself held longitudinally immovable relative to the shaft 48) will cause the head 76 to move backward or forward in the slot 74 and move therewith the rod 80. The rod 80 will operate the key 56 to cause the disk or spider 54 to connect or disconnect the halves 44 and 50 of the clutch 46 to cause the rotation or non-rotation of the shaft 48.
- 25 The bearing portion 60 has a laterally extending flange or portion 84 having suitable openings for the reception of bolts 86. Over the bolts 86 there are positioned the rollers 88. Between the rollers 88 and a cut-out portion 90 in the bearing portion 60, there are mounted the lift rack or bar 92 and the control rack or bar 94 meshing respectively with the gears 66 and 68. The rotation of the shaft 48 and its gear 66 will therefore cause 30 a movement of the lift rack 92 to raise or lower the load. As is best seen in Figure 1, the lift rack 92 has a rabbet 93 formed at one corner in which the control rack 94 is mounted. The control rack is reciprocably mounted on the rack 92 by means of the headed bolts 96. The purpose of the control rack 94 is to rotate the loosely mounted gear 68 to cause the engagement or disengagement of 35 the clutch 46.
- 40 The lift rack 92 extends downwardly from the hoist and has mounted at its end a loop or ring 98 adapted to be attached to the load. The loop 98 is swivelly mounted between a pair of collars 100 secured to the rack in any

suitable way as by means of the taper pins 102.

The lower end of the control rack 94 has pivotally mounted thereon as at 104 a handle 106 which surrounds the lift rack 92. A coil spring 108 mounted between the upper collar 100 and a shoulder 110 on the interior of the handle constantly urges the handle 106 and control rack 94 upwardly to cause the gear 68, head 76 and rod 80 to throw the clutch into engaging position. By moving the handle 106 in either direction, the control rack 94 and gear 68 may be moved to shift the rod 80 to operate the clutch.

Inasmuch as the control rack 94 is mounted on the rack 92, the two will ordinarily move in unison. There is only relative movement between the two racks when the operator positively raises or lowers the handle 106. Under normal operating conditions therefore the gears 66 and 68 turn together and with the shaft 48.

Adjacent its lower end the lift rack 92 is provided with a pair of fingers 112 and 114 which are spaced apart in vertical planes or secured to opposite sides of the rack. The function of the finger 114 is to strike the arm 116 of the switch when the rack reaches its uppermost position while the purpose of the finger 112 is to strike the arm 118 of the switch to throw on the motor when the rack 92 is pulled downward. The finger 114 therefore serves as a means for automatically throwing off the power from the motor 11 when the rack has reached its uppermost position. The lowering movement of the rack 92 is limited by the engagement of the gear 66 with the non-threaded end 119 of the rack.

The operation of the hoist is as follows: Assuming that the parts are in the position shown in Figure 2 (which is the uppermost position of the rack bar 92) the operator grasps the handle 106 and pulls it downward. This will rotate the gear 68 and cause the head 76 to move to the left (Figure 2) to disengage the clutch. At the same time the downward pull or movement of the handle will pull the rack 92 therewith and cause the finger 112 to strike the arm 118 to throw on the switch to start the motor, but as the clutch is released the motor will not operate the shaft 48. The handle 106 is held downward until the load is applied to the loop 98. The handle 106 is then released allowing the spring 108 to push the handle 106 and rack 94 upwardly, which will rotate the gear 68 and cause the head 76 to move to the right causing the disk 54 to push the clutch 46 into engagement. The motor 11 will now rotate the shaft 48 and its gear 66 which will raise the lifting rack 92 and cause the elevation of the load. The raising of the load will continue either until the operator pulls downward on the handle 106 or until the finger 114 strikes the arm 116 of the switch. As the finger strikes

the arm 116, the motor will be thrown off and due to the irreversible connection between the worm 20 and the worm wheel 28, the load will be maintained suspended in the air. If it is now desired to release the load, the operator will pull down on the handle 106 to operate the control rack 94 which rotates the gear 68, moving the rod 80 to the left to disengage the clutch. The load is now free to descend owing to the fact that the released clutch 46 is between the worm and the rack. The finger 112 on the rack will again throw the switch to start the motor and if it is desired to stop the load at any intermediate point, the operator may release the handle 106 which will again throw in the clutch to cause the motor to raise the load. The operator may therefore deposit the load at any desired point and after the load is deposited and the handle 106 released, the hoist will again move in the position shown in Figure 2. In case it is not desired to raise the load to the limits of the hoist, the clutch may be disengaged at any intermediate point by pushing the handle 106 upwardly. The load will then descend to the bench or block as desired.

The hoist of the invention is relatively light and is particularly adaptable to the raising of the light loads or such loads as are not ordinarily within the handling ability of the workmen, such as loads of 200 or 300 pounds.

I claim:

1. In a swingably suspended hoist, a shaft operated from a source of power, a bar vertically reciprocably operated from said shaft, means on said bar for attaching a load, a clutch for connecting the power to or disconnecting it from the shaft to control the movement of the bar, and means to operate the clutch.

2. In an overhead swingably suspended hoist, a shaft operated from a source of power, a bar operated from said shaft and adapted to lift a load, and means including a reciprocable member on said bar for connecting and disconnecting said shaft with the source of power to control movements of said bar.

3. In a hoist, a shaft operated from a source of power, a gear on said shaft, a rack meshing with and operated from said gear, means on said rack to attach a load, a clutch connecting the source of power and the shaft, and means concentric with the shaft for operating said clutch to connect or disconnect said source of power and shaft.

4. In a hoist, a shaft operated from a source of power, a bar operated from said shaft and adapted to raise a load, a clutch between said source of power and said shaft, and means concentric with said shaft and operable from said bar for operating said clutch to connect or disconnect said source of power and shaft.

5. In a hoist, a shaft operated from a source of power, load elevating means operated from said shaft, a clutch between said source of power and said shaft, and means operated from said load elevating means for connecting or disconnecting said clutch to control said load elevating means.

6. In a hoist, a shaft operated from a source of power, load elevating means operated from said shaft, a clutch between said source of power and said shaft, and means concentric with said shaft and operable from said load elevating means for connecting and disconnecting said clutch.

7. In a hoist, a shaft operated from a source of power, load elevating means operated from said shaft, a clutch between said source of power and said shaft, a gear freely mounted on said shaft, means projecting from said shaft and moved by said gear, means operated from said projecting means to connect or disconnect said clutch, and means for operating said gear.

8. In a hoist, a shaft operated from a source of power, load elevating means operated from said shaft, a clutch between said source of power and said shaft, a rotatable member freely mounted on said shaft, means projecting from said shaft and operated by said member to operate said clutch, and means for rotating said member.

9. In a hoist, a shaft driven from a source of power, load elevating means operated from said shaft, a clutch between said source of power and said shaft, a rotatable member freely mounted on said shaft, a member projecting from said shaft and having threaded engagement with the interior of said rotatable member, a rod connected to said projecting member and adapted to operate said clutch, and means for rotating said rotatable member.

10. In a hoist, a shaft driven from a source of power, load elevating means operated from said shaft, a gear internally and externally threaded and loosely mounted on said shaft, a threaded head mounted in a slot in and projecting from said shaft and engaging the internal threads on said gear, a clutch for connecting and disconnecting said shaft with the source of power, a rod secured to said head and extending centrally of said shaft and adapted to operate said clutch, and means on said load elevating means for rotating said gear.

11. In a hoist, a shaft driven from a source of power, load elevating means operated from said shaft, a gear internally and externally threaded and loosely mounted on said shaft, a threaded head mounted in a slot in and projecting from said shaft and engaging the internal threads on said gear, a clutch for connecting and disconnecting said shaft with the source of power, a rod secured to said head and extending centrally of said shaft

and adapted to operate said clutch, and a rack reciprocably mounted on said load elevating means for rotating said gear.

12. In a hoist, a shaft driven from a source of power, load elevating means operated from said shaft, an element parallel with and secured to said elevating means, and means manually operable from said element to connect or disconnect said shaft and source of power.

13. In a hoist, a shaft driven from a source of power, a reciprocable load elevating bar operated from said shaft, a clutch between said source of power and shaft, means for operating said clutch, a bar parallel with said elevating bar and adapted to operate said means, and a handle on said elevating bar to operate said second named bar.

14. In a hoist, a shaft driven from a source of power, a reciprocable load elevating bar operated from said shaft, a clutch between said source of power and shaft, means for operating said clutch, a bar parallel with said elevating bar and adapted to operate said means, a handle on said elevating bar to operate said second named bar, and resilient means operating on said handle and urging said handle and bar to move said means to clutch engaged position.

15. In a hoist, a shaft driven from a source of power, a clutch between said shaft and source of power, a gear rigid with said shaft, a gear loosely mounted on said shaft, a load elevating bar meshing with and operated by said rigidly mounted gear, a control bar reciprocably mounted on said elevating bar and engaging said loosely mounted gear, and means operated on the reciprocation of said control bar to engage or disengage said clutch.

16. In a hoist, a shaft driven from a source of power, a clutch between said shaft and source of power, a gear rigid with said shaft, a gear loosely mounted on said shaft, a load elevating bar meshing with and operated by said rigidly mounted gear, a control bar reciprocably mounted on said elevating bar and engaging said loosely mounted gear, a handle around said elevating bar and attached to said control bar for reciprocating said control bar to operate said loosely mounted gear, and means operated by said gear to engage or disengage said clutch.

17. In a hoist, a shaft driven from a source of power, a clutch between said shaft and source of power, a gear rigid with said shaft, a gear loosely mounted on said shaft, a load elevating bar meshing with and operated by said rigidly mounted gear, a control bar reciprocably mounted on said elevating bar and engaging said loosely mounted gear, means operated on the reciprocation of said control bar to engage or disengage said clutch, and means on said elevating bar adapted to throw off the source of power when said bar is at one extremity of its movement.

18. In an overhead freely swingable hoist, a housing, a shaft mounted in said housing and extending beyond both sides thereof and driven from a source of power rigidly mounted relative to said housing, a clutch at one end of said shaft between said source of power and shaft, a gear rigidly mounted on the opposite end of said shaft, a load elevating rack meshing with and operated from said gear, and means on the gear end of the shaft for connecting or disconnecting said clutch.

19. In an overhead freely swingable hoist, a housing, a shaft mounted in said housing and extending beyond both sides thereof and driven from a source of power rigidly mounted relative to said housing, a clutch at one end of said shaft between said source of power and shaft, a gear rigidly mounted on the opposite end of said shaft, a load elevating rack meshing with and operated from said gear, a rod in said shaft connected to said clutch, means at the gear end of said shaft for operating said rod, and means for operating said first named means.

In testimony whereof I affix my signature.
ELVIN S. GOODSPEED.
